LAVATORY

Carl S. Dailey, 583 E. Thelborn, Covina, Calif.

Filed Oct. 3, 1960, Ser. No. 62,332

Term of patent 14 years

(Cl. D4—2)

Fig. 5.

Fig. 6.

FIG. 1 is a side elevational view of a lavatory, partly in cross-section, showing my new design.

FIG. 2 is an enlarged fragmentary front elevational view of the spout portion thereof.

FIG. 3 is an enlarged fragmentary side elevational view of the spout portion thereof, partly in cross-section.

FIG. 4 is an enlarged cross-sectional view of the spout portion thereof taken on line 4—4 of FIG. 2.

FIG. 5 is an enlarged top plan view of the spout portion of the lavatory.

FIG. 6 is a plan view of the lavatory at about half the scale of FIG. 1.

The dominant features of my design reside in the portions shown in full lines on the drawing.

I claim:

The ornamental design for a lavatory, substantially as shown and described.
